Primary Examiner — T. Chase Nelson*Assistant Examiner* — Jonathan J Han(74) *Attorney, Agent, or Firm* — QuickPatents, LLC;
 Kevin Prince(57) **CLAIM**

I claim the ornamental design for a keychain stun gun, as shown and described.

DESCRIPTION

FIG. 1 is a front perspective view of a keychain stun gun showing my new design;

FIG. 2 is a rear perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The broken lines showing a keychain, logo and charging port in the figures depict environmental matter and form no part of the claimed design.
